UNITED STATES PATENT OFFICE.

AUGUST LOMBARDO, OF WASHINGTON, IOWA.

BANANA-CRATE.

No. 868,790.

Specification of Letters Patent.

Patented Oct. 22, 1907.

Application filed January 16, 1907. Serial No. 352,637.

To all whom it may concern:

Be it known that I, AUGUST LOMBARDO, a citizen of the United States, residing at Washington, in the county of Washington and State of Iowa, have invented 5 certain new and useful Improvements in Banana-Crates, of which the following is a specification, reference being had therein to the accompanying drawing.

This invention relates to an improvement in shipping receptacles or crates, and particularly to a banana crate. 10 The object of the invention is the provision of means for facilitating the handling and shipping of a bunch of bananas, without liability of injuring the same.

With this and other objects in view, the invention consists of certain novel constructions, combinations, 15 and arrangements of parts, as will be hereinafter fully described and claimed.

In the drawings: Figure 1 is a view in side elevation of a crate constructed in accordance with the present invention. Fig. 2 is a transverse, vertical, sectional 20 view of the structure of the crate depicted in Fig. 1. Fig. 3 is a plan view of the bottom of the crate. Fig. 4 is a fragmentary, sectional view of the crate taken on line 4, 4, Fig. 2.

In carrying out the present invention, I have assembled 25 two slatted, cylindrical sections together, one within the other, and secured these sections together only at their ends; the outer section being formed of stiff or stronger material than the inner section, whereby said outer section forms a protector or shield for the 30 inner section, which inner section has the bag or sack secured thereto, as hereinafter described.

Referring to the drawings by numerals, 1 designates the outer protecting-section, and 2 the inner section. The outer protecting-section comprises longitudinal 35 panels 3 and a series of outer hoops 4. Two of the hoops 4 are secured at the ends of the panels or strips 3. The panels or strips are spaced apart for forming a slatted, cylindrical section.

The inner or bag-carrying section 2 comprises longitudinal 40 panels or strips 5 intermediate hoops 6. Two of the intermediate hoops 6 are secured at the ends of the panels or strips 5. The hoops 4 and 6 are preferably positioned parallel. Inner hoops 7 are secured within the inner, slatted section 2, and at its ends, 45 parallel with the end-hoops of the outer and inner sections 1 and 2, respectively. The inner hoops 7 constitute reinforcing means for the end of the crate, as well as assisting in securing the ends of the inner and outer sections together.

50 It will be noted that the crate is of a sectional structure, the sections of which are only secured at the ends, because, while all of the end hoops of the outer and in-

ner sections 1 and 2, respectively, are secured together, the intermediate hoops of each section are only secured to the panels or strips of its respective section.

55

A bag or sack 8 of any preferred structure, suitable to accommodate a bunch of bananas, is placed within the inner section 2 and secured, intermediate its ends, to the inner section 2, by means of preferably flexible loops 9. Each intermediate hoop of the inner section 60 2 is provided contiguous to each panel or strip 5 with a pair of horizontal apertures 10, through which one of said loops 9 is threaded, see Fig. 4. By reason of the fact that the hoops of the inner section 2 are parallel with the hoops of the outer section 1, the outer part or 65 knot 9' of each loop 9 is placed behind a panel or strip 3 and a hoop 4, thereby preventing the loop 9 from being cut or injured by any object coming in contact with the outer protecting-section 1. The panels or strips 3 of the outer or primary section 1 are formed of comparatively thick or stiff material, so as to produce a stiff or rigid outer section, while the inner section has its 70 panels 5 formed of material having sufficient resiliency to permit a panel or panels of said sections to be slightly bent inward, acting as a cushion for a bunch of bananas 75 carried by the bag 8, when the crate is suddenly jarred or roughly handled. It will, therefore, be noted that the bag 8 is suspended or supported intermediate its ends, upon a resilient, inner section, which inner section permits the bag to have a slight, lateral movement 80 upon either of its sides, as the weight of a bunch of bananas contained therein, is brought to bear upon any side of the bag. A portion of the lower end 8' of the bag 8 is secured between the lower, inner, reinforcing hoop 7 and the lower ends of the panels or strips 5, as 85 clearly seen in Fig. 2. By reason of the positioning of the lower or open-end 8' of the bag between the inner hoop and the lower end of the inner section 2, the mouth of the bag can be easily and quickly opened and a bunch of bananas placed in the bag by a single operator. 90

In the claims, I have designated the crate or sections thereof as being of a "slatted" structure, which means that the sections are formed of longitudinal panels preferably held together by hoops. The panels or 95 strips 3 and 5 of the outer and inner sections constitute slats.

What I claim is:

A banana crate, comprising an outer, cylindrical and an inner cylindrical section, each section comprising longitudinal panels and intermediate and end-hoops positioned thereon, inner hoops positioned within and at the ends of the inner section and parallel with the end hoops of the inner and outer sections, means fixedly securing the end-hoops of the inner and outer sections and the inner hoops 100 105

together, means fixedly securing the intermediate hoops of the outer section only to the panels of said outer section, means fixedly securing the intermediate hoops of the inner section only to the panels of the inner section, a bag positioned within the inner section, one of the inner hoops positioned within said bag, whereby a portion of the bag is positioned between an inner hoop and the panels of the inner section, each intermediate hoop of the inner section provided with a pair of apertures contiguous to each

panel, and loops secured to the bag and threaded through the apertures of the intermediate hoops and positioned behind the intermediate hoops of the outer section. 10

In testimony whereof I hereunto affix my signature in presence of two witnesses.

AUGUST LOMBARDO.
